METAL CONTAINER

Filed Sept. 20, 1930

FIG. 4. 14. 73

Inventor

T. C. FOGARTY.

Starts, Vant Mason & Porter, Attorneys

UNITED STATES PATENT OFFICE

THOMAS C. FOGARTY, OF KEW GARDENS, NEW YORK, ASSIGNOR TO CONTINENTAL CAN COMPANY, INC., OF NEW YORK, N. Y., A CORPORATION OF NEW YORK

METAL CONTAINER

Application filed September 20, 1930. Serial No. 483,352.

The invention relates to new and useful improvements in metal containers, and more particularly to an easy opening container.

It has been a common expedient to provide a container with score lines in the body wall setting off a tearing strip and to apply to the tearing strip a key for removing the same. The key in order to be readily accessible for opening the can has been fixedly secured to the cover so as to become a part of the container unit.

An object of the present invention is to provide a container which is so constructed that the key may be rigidly attached thereto without requiring any particular placing of the key other than radially of the cover, and wherein said cover is also so constructed that the fingers may be readily forced beneath the handle of the key for raising the same and breaking its connection with the cover.

In the drawings:—

Figure 1 is a view partly in section and partly in side elevation of the upper portion of the container embodying the improvements.

Fig. 2 is a plan view of the container shown in Fig. 1.

Fig. 3 is an enlarged sectional view through a portion of the cover and the side wall of the container.

Fig. 4 is a sectional view through the cover showing a slightly modified shaping of the cover.

The invention resides in a metal container which consists of a body portion 1 to which a cover 2 is attached by means of a double seam 3. This cover is provided with score lines 4, 4 setting off a tearing strip 5 of the usual construction. The container as illustrated in the drawings is provided with an inserted member 6 formed by folding a piece of metal back on itself and providing the upper edge thereof with a rolled bead 7. This member 6 is attached to the body and becomes a part thereof. The cover is provided with a depending flange 8 formed by drawing the metal in the cover. When the rip strip 5 is removed the cover can be placed on the can body for reclosure purposes. The depending portion 8 will slide down on the

outer side of the inserted member 6 thus making an outside slip reclosure. The features just described in detail form no part of the present invention except to illustrate one form of easy opening container wherein the cover is released by the removal of a tearing strip.

In this type of container the tearing strip is removed by means of a key 9 which is formed in the shank thereof with a slot 10 adapted to be inserted on the end of the tearing strip. The key is provided with a handle 11 by which it may be forcibly turned for rolling the tearing strip onto the shank of the key. This is a common form of key used for removing the tearing strip. The shank portion is flattened so as to give sufficient width thereto for the slot 10 therethrough. The cover is provided with a raised portion 12 located centrally of the cover. The inner end 13 of the key as shown in the drawings is attached to this raised portion 12 by means of solder 14. It can be welded or secured thereto in any other way in order to form a rigid attachment of the key to the cover. Even the key itself or the attaching means is so formed that it may be ruptured when the key is forcibly lifted and turned toward a vertical position. The cover has a portion 15 which is depressed slightly relative to the plane of the outer portion of the cover so that this raised portion 12 is substantially in the plane of the outer portion of the cover.

The cover is provided with an annular recess or depression 16 which is concentric to the center of the cover and which is so disposed in the cover that when the key is attached thereto the handle 11 will overlie this annular recess or depression 16. It makes no difference how the key is placed on the cover, whether in the full line position shown in Fig. 2, or in the dotted line position indicated at 9*. The inner end is at the center of the can, and the handle end of the key overlies this groove or depression. It is important, however, that the key shall be placed radially of the cover.

From the above construction it will be apparent that keys may be attached to covers automatically, and all that it is necessary in

- the automatic machine for accomplishing this result is to place the key radially of the cover with the inner end at the center thereof. So far as the placing of the cover is concerned, 5 there is no particular positioning required other than that the key shall when assembled with the cover will take the position which has been indicated above. After the key is soldered to the cover and the cover placed 10 on the container body it becomes a unit with the container. When it is desired to open the container the operator inserts the fingers beneath the handle of the key in this groove or depression 16 which is of sufficient depth to 15 allow the fingers to be readily forced underneath the handle of the key for the lifting of the key. Thus it is that the key may be forcibly raised toward vertical position and the solder bond broken.
- 20 In Fig. 4 of the drawings the portion 15 of the cover and the outer portions of the cover are in the same plane. The handle 11 of the key overlies the annular groove or depression 16 and may extend slightly beyond said 25 groove. The groove serves the same purpose of permitting the fingers to be forcibly inserted beneath the handle for the raising of the same toward vertical position for breaking the solder bond.
- 30 While I have shown the key as formed of wire which is flattened to provide the shank portion and curved to provide a handle, it will be understood that it may be formed in any other desired way. While I have shown 35 a solder bond for joining the key to the cover, it will be understood that it may be joined in other ways, and other means provided for rupturing the metal to release the key from the cover.
- 40 Having thus fully described my invention, what I claim as new and desire to secure by Letters Patent, is:—
1. An easy opening metal container comprising a body portion having score lines adjacent one end thereof setting off a tearing strip, a cover seamed to said body portion, a key for removing said tearing strip having a handle at its outer end and arranged radially on said cover with its inner end secured to the 45 center portion of the cover, said cover having an annular depression concentric to the center of the cover and extending beneath the handle of the key whereby the fingers may be forcibly inserted beneath the handle and 50 the key raised toward vertical position for breaking its connection to the cover.
  2. An easy opening metal container comprising a body portion having score lines adjacent one end thereof setting off a tearing 55 strip, a cover seamed to said body portion and having a raised portion centrally thereof, a key for removing said tearing strip having a handle at its outer end and arranged radially on said cover and rigidly secured at its 60 inner end to said raised portion, said cover

having an annular depression concentric to said raised portion and extending beneath the handle of the key whereby the fingers may be forcibly inserted beneath the handle and the key lifted for breaking its connection to the cover.

In testimony whereof I affix my signature.
THOMAS C. FOGARTY.
